UNITED STATES PATENT OFFICE.

REINHOLD GRABEIN, OF FORST, LUSATIA, GERMANY.

THREAD MADE FROM HORSEHAIR AND PROCESS OF FORMING THE THREAD.

1,057,725.

Specification of Letters Patent.

Patented Apr. 1, 1913.

Application filed October 30, 1912. Serial No. 728,564.

To all whom it may concern:

Be it known that I, REINHOLD GRABEIN, a subject of the King of Prussia, residing at Richtstrasse 9, Forst, Lusatia, Germany, have 5 invented new and useful Improvements in Thread Made from Horsehair and Processes of Forming the Thread, of which the following is a specification.

This invention relates to thread made from 10 horsehair and to the process of forming the thread.

One of the objects of the invention is to provide a thread of this character in which the horse hairs of which the thread is composed cannot be withdrawn and in which the ends of the hairs will not project through 15 the covering of the thread.

Another object is to provide a simple 20 method by which such a thread may be made.

Other objects will in part be obvious and in part be pointed out hereinafter.

Referring to the accompanying drawings, 25 Figure 1 represents a machine by means of which the process may be carried out. Fig. 2 shows on a greatly enlarged scale, the form which the hair acquires after being curled or corrugated. Fig. 3 is a sectional view of a thread drawn to a greatly enlarged scale. Fig. 4 is a view similar to 30 Fig. 3 showing a slightly modified form of thread.

According to the usual practice, when 35 horse hair is formed into a thread, it will, if the thread is bent, work loose, as a result of which the ends of the hairs will project from the thread or from the cloth fabric made from the thread. This feature is a 40 very disagreeable one, especially where the fabric formed of horsehair thread is used for the lining or stiffening of clothes, as the projecting ends of the hair are apt to stick into the body of the person wearing the clothes. Furthermore, the hairs can be 45 easily drawn out of the fabric, thus destroying the stiffening quality of the same. These disadvantages increase as the length of the hairs which are used decreases. In other words, the shorter the hairs which form the 50 thread, the more pronounced will be the working out of the hairs.

The principal feature of this invention 55 is to provide a thread, and a process of forming the same which will avoid the above mentioned disadvantages of the ordi-

nary horse hair thread and the fabric constructed therefrom.

By way of example, in order simply to illustrate the process, there is shown a hair feeding apparatus such as is described and 60 claimed in applicant's co-pending application, Serial #602,617, filed January 14th, 1911, to which application reference is made for a detailed description of the apparatus. It will, of course, be understood that the 65 process or the article is not limited in any way to this particular form of apparatus, as, of course, other apparatus might be used without in any way departing from the spirit of the invention.

Referring to Fig. 1 of the drawing, 1 represents a trough in which the horse hairs are placed and which is provided with a longitudinal slot formed in its bottom, through which slot the ends of the pincers 2, 70 mounted upon a rotatable disk 3 may pass, as described in the above referred to application. These pincers open as they enter the slot in the trough, then close so as to grip one or more of the hairs in the trough 75 to feed the same forward, and then again open in order to release the hair or hairs, as the ends thereof engage between the roughening or corrugating rollers 4. The hairs may be fed to the rollers singly, or if desired, two or more hairs may be fed at one 80 time and the hairs are so fed that they will overlap the preceding hairs. As the hairs 85 pass through these rollers, they will, of course, be curled or corrugated, as clearly 90 shown in Fig. 2 and the overlapping portion of the hairs will, to a certain extent, interlock with one another as illustrated in Fig. 3. If a plurality of hairs are fed to the corrugating rollers at each rotation of 95 the pincers, the hairs of each set will, of course, be similarly waved or corrugated and will interlock with one another and the overlapping ends of the sets of hairs will 100 also interlock with one another as clearly 105 shown in Fig. 4. After passing through the rollers 4, the roughened or corrugated hairs 5 are led through a funnel 6, from which they pass through a hollow spindle 7 of any approved construction. Before passing 110 through the hollow spindle, the hairs are wound about with binding thread 8 in the well known manner. This binding thread will, of course, lie in the corrugations formed in the hairs, as shown in Figs. 3 115

and 4, and will serve to hold the individual hairs firmly in position, from which it will be understood that not only are the free ends of the hairs held against projecting out of the finished thread which emerges from the lower end of the hollow spindle, but the hairs will be so firmly held in position in the finished thread that their withdrawal therefrom will be impossible. Even if the 10 thread should be cut at a point intermediate the ends of one of the hairs, the cut ends cannot project from the thread, as they will be held in position by reason of the corrugations with which the binding thread engages.

Having described the invention to the details of which disclosure, it is not, of course, to be limited, what is claimed as new and what is desired to be secured by Letters Patent, as set forth in the appended claims:—

20 1. A thread comprising corrugated horse hairs in overlapping relation to one another

and a binding thread wound around said hairs.

2. A thread comprising corrugated horse hairs in overlapping relation to one another, the corrugations of the overlapping portions of the thread interlocking with one another, and a binding thread wound around said hairs.

3. The herein described method of forming a thread from horse hairs which consists in feeding the hairs in overlapping relation to one another, corrugating the hairs and winding a binding thread about the corrugated hairs.

In testimony whereof I have signed my name to this specification in the presence of two subscribing witnesses.

REINHOLD GRABEIN.
